W. TURTON.

Hot-Air Register.

No. 8,811.

Patented March 16, 1852.

UNITED STATES PATENT OFFICE.

WILLIAM TURTON, OF BUSHWICK, NEW YORK.

HOT-AIR REGISTER.

Specification of Letters Patent No. 8,811, dated March 16, 1852.

To all whom it may concern:

Be it known that I, WILLIAM TURTON, of the town of Bushwick, county of Kings, and State of New York, have invented a new and useful Improvement in a Hot-Air Register and Ventilator, and which I denominate "Turton's Improved Hot-Air Register and Ventilator"; and I hereby declare the following to be a full, clear, and explicit description, reference being had to the annexed drawings, making a part of this specification, in which—

Figure 1 is a perspective view of the movement with the rim or frame, and a half section of the top or fretwork.

Figure 2 is a detached fan with wheel affixed or cast on.

Figure 3 is a crown wheel.

Figure 4, is a center piece for bearings 20 for the fan.

Figure 5 is a star or cross finger piece.

6 is a washer which upholds the fans to the center piece and keeps them in place.

In the principal figure, *a* corresponds to 25 Figure 2, *b*, *c*, and *d*, corresponds to Figures 3, 4, and 5, respectively, and *e* is the outside rim or frame.

The nature of my invention consists in 30 furnishing a crown wheel and gearing it directly to the fans by means of a pinion wheel, or section of the same, attached to each fan, by which the fans are made to open and shut in an easy, accurate and uniform manner.

I construct my register or ventilator of 35 iron or other material, in a circular, octagon or other form, with a rim or box and fret-

work top in the usual manner. The fans I make in a sector form, with pins at each end, one resting in the rim, through which 40 holes are drilled for that purpose, and the other on the center piece.

I make the fans eight in number, or more or less, and attach to them wheels or sections of wheels. From the top a center shaft is 45 projected downward, to the bottom of which the center piece and fans are secured by a screw and washer. Around this shaft the crown wheel revolves, and being geared into the fans, is moved by the cross or star, 50 the arms of which pass down to it through the fretwork. The cross or star is countersunk to receive a pin on top of the shaft, which assists to steady the motion of the wheel. Thus by a slight pressure of the 55 cross, or star, finger piece, I am enabled by turning it one eighth of a circle to move the crown wheel sufficiently to open or shut the whole number of fans: The lips on the fans serving as a stop, when closed; and the projecting arms of the finger piece, against portions of the fretwork, answering the same 60 purpose, when they are fully opened.

What I claim, and desire to secure by Letters Patent is—

The crown wheel or section of a crown wheel, in combination with the pinion wheel or section of wheel attached to the fans, as set forth.

WILLIAM TURTON.
